UNITED STATES PATENT OFFICE.

EDWARD H. SCHWARTZ, OF CHICAGO, ILLINOIS, ASSIGNOR TO KROESCHELL BROTHERS COMPANY, OF CHICAGO, ILLINOIS, A CORPORATION OF ILLINOIS.

GAS-GENERATING CRUCIBLE-FURNACE.

No. 910,091.

Specification of Letters Patent. Patented Jan. 19, 1909.

Application filed April 4, 1908. Serial No. 425,156.

To all whom it may concern:

Be it known that I, EDWARD H. SCHWARTZ, a citizen of the United States of America, and resident of Chicago, Illinois, have invented a certain new and useful Improvement in Gas-Generating Crucible-Furnaces, of which the following is a specification.

My invention relates to improvements in gas generating crucible furnaces, and has for its object the production of a device by the use of which the melting of metals is greatly facilitated.

A further object is the production of a device by means of which air and steam may be freed from moisture before being forced into the combustion chamber.

A further object is the production of a device of simple construction, the parts of which may be readily assembled and disassembled.

A further object is the production of a device in which practically perfect combustion may be effected and a maximum of results obtained with a minimum of fuel.

A further object is the production of a device that is of durable character and one that is least liable to disarrangement of parts.

These and such other objects as may hereinafter appear are attained by the use of my device, an embodiment of which is illustrated in the accompanying drawings, in which—

Figure 1 represents a side elevation of my device. Fig. 2 is a top plan view, with the muffler hood out of position. Fig. 3 is a sectional view on line 3—3 of Fig. 1, looking in the direction indicated by arrows. Fig. 4 is a sectional view on line 4—4 of Fig. 3, looking in the direction indicated by arrows. Fig. 5 is a bottom plan view of my device, showing the hinged beveled door. Fig. 6 is an enlarged detail of the lower door catch.

Like numerals of reference indicate like parts in the several figures of the drawing.

Referring now by numerals to the accompanying drawings—7 represents an outer casing or shell preferably cylindrical in shape, having an inner lining 8 with a lining 9 inside of fire-brick or some refractory material. The upper portion of the lining 9 extends vertically while the lower portion slopes inwardly, forming a conical fire-pot. The furnace is provided with a base plate 10,

to which the shell or casing 7 is bolted as at 11. A lug or dam 12 extends upwardly from the face of the plate 10 a short distance from the outer edge thereof, while a supplemental casing of metal 13 extends from inside the casing 7 sloping downwardly outside the lining 8, and extending within the lug or dam 12. A space 14 is thus formed between the supplemental casing 13 and the outer shell 7, the purpose of which will be explained later.

A beveled bottom door 15 is hingingly secured to the plate 10 by means of hinges 16, as clearly shown in Fig. 5. The plate is also provided with abutments 17, thus insuring a tight joint between the edges of the door and the walls of the plate. This door is held in place by means of a catch 18 on the end of a lever 19. This catch 18 normally rests against the edge of the door 15, holding it securely in place. This door is conical in shape, and is preferably provided at its lower extremity with an opening 20.

A plurality of twyer openings 21 extend through the shells and supplemental casing, making open connection between the air space 14 and the inner chamber of the furnace.

A top plate 22 provided with a circular opening is secured to the top of the furnace, preferably by means of angle irons 23, as shown in Fig. 1. A removable inner top plate 24 is seated on top of the lining 8—9, the removal of which permits the placing of the brick within the furnace without taking off the door 25. This door comprises an outer shell 26 and an inner brick lining 27, and is hingingly secured to the lug 28—preferably cast on the top plate 22. A lever lug 29 is also cast on the door plate within which the lever 30 may be inserted, allowing the door to be easily raised. The door is provided with a central opening 31 through which the products of combustion pass when the furnace is in operation. An air supply pipe 32 provided with a gate-valve 33 enters the lower part of the supplemental chamber 14 tangentially so as to force the air therefrom about the chamber. A steam pipe 34 enters the air pipe 32 at 35, and is provided with a valve 36. This steam pipe terminates in a nozzle 37. The chamber 14 is provided with a discharge opening 38, from which extends a tube 39 preferably turned down-

wardly and terminating in a receptacle 40. A discharge pipe 41 leads from this receptacle. The mouth 42 of the pipe 39 is below the discharge pipe 41, forming a water-seal, 5 and preventing the escape of the air or gas from the compartment 14 or the admission of atmospheric air therein.

A muffler hood 43, of a substantially spherical shape, is removably located just above 10 the opening 31. A pipe 44 connects the top of the muffler hood with a discharge pipe 45. This discharge pipe is preferably provided with running water, as shown at 46. This muffler and pipe 44 is swingingly connected 15 with the top or flue of the pipe 45, as shown at 47.

Referring to the operation of my device, the kindlings and coal are placed within the bottom part of the combustion chamber, as 20 shown at 48, and a crucible 49 placed within the combustion chamber 50 and seated on top or pressed a little within the body of the coals 48. The cover or door at the top is then closed, and the fire started in the combustion chamber. As soon as the fire is well under way, air—or air and steam—is introduced through the pipe 32 into the supplemental chamber 14. This current is forced 25 in, tangentially, and through action of centrifugal force is thrown against the inside of the outer casing, through which operation all of the moisture within the air or steam is caused to collect at the bottom of the chamber between the dam 12 and the casing, from 30 which it is drawn off through the discharge pipe 39. The mixture of air and dry steam is then forced through the twyers into the lower portion of the combustible material, and upwardly 35 therethrough, thus accelerating the combustion and forming practically a gas generating machine. It is evident that if desired, the introduction of steam may be done away with and only air pressure used, which may 40 be obtained from a fan or blower in any well known way. I find, however, that by the introduction of steam the generation of gas is accelerated. The amount of pressure of the gas and air introduced can be regulated 45 by means of the valves shown. As the fuel is partially consumed, it settles down to a slight degree, the crucible fitting closely within the center of the material. The lower portion of the combustion chamber—or practically the fire-pot—being conical in shape 50 serves to cause the fuel to pack more closely and prevent any tipping or movement of the crucible within the combustion chamber. By the use of this form of furnace, an intense 55 heat is produced, and by exercising care in charging the furnace, sufficient material may be placed therein at the beginning of the operation making it unnecessary to open the door until the charge is melted and the cru-

cible ready for removal. In the event that 65 the crucible breaks, the molten material will pass down through the coals and escape through the opening 20.

The lining of the furnace is formed in two layers, one practically continuous layer 8 70 preferably of fire clay or brick, with an inner sectional lining 9, thus making it necessary to renew only the inner lining. It will thus be noted that the outer lining always remains in the furnace, it being necessary only 75 to remove the inner lining (which is generally of cheap material), and making the expense of repairs and renewal very small.

The removable ring 24 seated on top of the fire-brick or lining can be readily removed when necessary to relin the furnace, and the fire-brick or other material used for the lining 9 slipped in place.

The door fits snugly about the top of the furnace, and is provided on its upper surface 85 with a lever lug 29, by means of which a lever may be inserted therein and open the door without exercising an undue amount of force. The beveled bottom 15, it will be noted, fits snugly about the bottom plate 10, 90 and is also readily operable, for the purpose of removing ashes, through the medium of the lever and latch mechanism shown in Figs. 5 and 6.

While I have shown a particular form of 95 mechanism in this instance, it is evident that there are many other forms which would be equally applicable to effect the desired result.

By the use of the muffler hood 43, much 100 of the noise incident to the operation of the furnace is done away with, while at the same time the products of combustion passing through the opening 31 are collected therein and carried through the pipe 34 to the flue 105 45. This flue or pipe is preferably so arranged that running water is always in the bottom of the flue, by means of which what would otherwise be waste products of combustion are condensed and saved. For instance, in the melting of brass, the zinc 110 oxids contained in the fumes are readily condensed, forming zinc white, which may be recovered and used in the mechanic arts.

I claim:

1. In a furnace, the combination with a casing, a combustion chamber, a supplemental chamber surrounding said combustion chamber, twyers intercommunicating between said chambers, and means for introducing fluid tangentially within said supplemental chamber.

2. In a furnace, the combination with a casing, a combustion chamber, a supplemental chamber surrounding said combustion chamber, twyers intercommunicating between said chambers, means for introducing fluid within said supplemental chamber,

and means for removing any accumulated liquid from said supplemental chamber.

3. In a furnace, the combination with a casing, a combustion chamber, a supplemental chamber surrounding said combustion chamber, twyers intercommunicating between said chambers, means for introducing fluid within said supplemental chamber, and means for removing any accumulated liquid from said supplemental chamber and at the same time preventing the admission of air thereto or the escape of fluid therefrom through said means.

4. In a furnace, the combination with a casing, a combustion chamber, a sectional lining of refractory material, a supplemental chamber surrounding said combustion chamber, twyers intercommunicating between said chambers, means for introducing fluid within said supplemental chamber, and means for removing any accumulated liquid from said supplemental chamber and at the same time preventing the admission of air thereto or the escape of fluid therefrom through said means.

5. In a furnace, the combination with a casing, a combustion chamber, an outer lining, an inner sectional lining of refractory material, a supplemental chamber surrounding said combustion chamber, twyers intercommunicating between said chambers, means for introducing fluid within said supplemental chamber, and means for removing any accumulated liquid from said supplemental chamber and at the same time preventing the admission of air thereto or the escape of fluid therefrom through said means.

6. In a furnace, the combination with a casing, a combustion chamber, a hinged bottom therefor, an outer lining, an inner sectional lining of refractory material, a supplemental chamber surrounding said combustion chamber, twyers intercommunicating between said chambers, means for introducing fluid within said supplemental chamber, and means for removing any accumulated liquid from said supplemental chamber and at the same time preventing the admission of air thereto or the escape of fluid therefrom through said means.

7. In a furnace, the combination with a casing, a combustion chamber, a hinged door or cover, a hinged bottom for said chamber, an outer lining, an inner sectional lining of refractory material, a supplemental chamber surrounding said combustion chamber, twyers intercommunicating between said chambers, means for introducing fluid within said supplemental chamber, and means for removing any accumulated liquid from said supplemental chamber and at the same time preventing the admission

of air thereto or the escape of fluid therefrom through said means.

8. In a furnace, the combination with a casing, a combustion chamber, an outer lining, an inner sectional lining of refractory material, a covering plate, a removable ring within said plate seated upon the top of said lining, means for introducing air and steam within said chamber, and means for withdrawing the moisture from said air and steam.

9. In a furnace, the combination with a casing, a combustion chamber, a cover, a hinged bottom provided with an opening in the apex thereof, means for introducing air and steam within said chamber, and means for withdrawing the moisture from said air and steam, together with means for raising said cover comprising an apertured lug adapted to receive a lever therein.

10. In a furnace, the combination with a casing, a combustion chamber, means for introducing air and steam within said chamber, means for withdrawing the moisture from said air and steam, and a crucible adapted to rest on coals within said combustion chamber.

11. In a furnace, the combination with a casing, a combustion chamber, an outer lining, an inner sectional lining of refractory material, means for introducing air and steam within said chamber, means for withdrawing the moisture from said air and steam, and a crucible adapted to rest on coals within said combustion chamber.

12. In a furnace, the combination with a casing, a combustion chamber, an outer lining, an inner sectional lining of refractory material, a covering plate, a removable ring within said plate seated upon the top of said lining, means for introducing air and steam within said chamber, means for withdrawing the moisture from said air and steam, and a crucible adapted to rest on coals within said combustion chamber.

13. In a furnace, the combination with a casing, a combustion chamber, a cover, a hinged bottom provided with an opening in the apex thereof, means for introducing air and steam within said chamber, and means for withdrawing the moisture from said air and steam, together with means for raising said cover, comprising an apertured lug adapted to receive a lever therein, and a crucible adapted to rest on coals within said combustion chamber.

Signed by me at Chicago, Illinois, this 31st day of March 1908.

EDWARD H. SCHWARTZ.
